POWER PUMP UNIT

Vaughan L. Andrew, Superior, Wis.

Application February 9, 1938, Serial No. 189,626

6 Claims. (Cl. 103—57)

This invention relates to pumping means and has special reference to one particularly adapted for household use or the like wherein but a relatively small and compact combined power and water pumping unit is desired.

The principal object of my present invention is the compacting of the two ends of the pump, in the art known as the power and water ends of such a pump.

10 Another object accomplished by such compacting of the two ends of the pump is that of overcoming the difficulties encountered where the ends of the pump are separated and which is substantially universal in this type of unit.

15 Still another object is to make more readily available those parts of such a unit which may need attention from time to time.

A further object is to provide such a unit wherein any leakage from the water end of the 20 pump is positively prevented from in any way interfering with the power end thereof, or vice versa.

25 Still other objects and advantages of the invention will appear in the following description thereof.

Referring now to the accompanying drawings, forming part of this application, and wherein like reference characters indicate like parts:

30 Figure 1 is a vertical central sectional view through one of the pump units, except that the upper portion of the section is offset from the center to illustrate the two intake water valves, one in section and the other in elevation, other portions of the unit also being shown in elevation.

35 Figure 2 is a horizontal section on the line 2—2, Figure 1, the crank pin being shown in horizontal position.

Figure 3 is a horizontal section on the line 3—3, Figure 1, with the cover of the power end removed, 40 and the crank pin 22 shown in horizontal position.

45 It is well known that in units of this type, driven either by an electric motor as here illustrated or a gasoline motor, trouble is experienced in keeping the stuffing glands of such a unit properly adjusted, and that, especially after some considerable time of use, and in such units where the power end is spaced from the pumping end with the piston exposed intermediate of the extremities of the unit as is common, water from the pumping end will follow the piston into the gland of the power end, causing interference with the normal functioning of the unit, the elimination of which it will appear I have accomplished in the 50 novel assembly here illustrated.

In the embodiment here illustrated I have shown at 1 the principal supporting housing, which is preferably of a single casting substantially rectangular in shape, though somewhat elongated, the power end embodying the chamber 2 and the pumping end the chambers 3—3, there being preferably a larger chamber 4 substantially the entire size of the interior of the housing beneath these chambers 2 and 3—3, separated therefrom as by the stepped floor or partition 5. 10 Intermediate of the chambers 2 and 3—3 is the vertical division wall 6 which is shown as a continuation of the floor 7 extending longitudinally and centrally of the bottom of the chambers 3—3 and providing the integral depending sleeve-like 15 support 7' for the power pitman 8. The floor 7 has a central upstanding integral portion 9 forming the pumping cylinder, the same being a portion of the division wall intermediate of the chambers 3—3, though preferably lined as with the 20 brass or other sleeve 10, and in which the pumping piston 11 is horizontally reciprocated as by the piston rod 12. This latter extends through its stuffing box 13 outwardly through the end wall of the housing and is rigidly connected as by the 25 coupling 14 to the similar outwardly extending end of the power pitman 8, so that these two members are in perfect parallel alignment and operate in unison. By this construction it is noted that the necessity of a stuffing gland for the pitman 8 is eliminated, and the peculiarity of this 30 construction will be described later.

The power chamber 2 of the housing is preferably provided with a removable covering member 15 which is held in place by any desired number 35 of tap or other bolts 16 through the various holes 17 in the housing, and the housing has extending laterally therefrom the sleeve or wrist-like journal 18, formed integral with the housing and also extending inwardly as well as outwardly therefrom. 40 Within this journal is mounted the hollow wrist pin 19 of the driving pulley 20 formed integrally therewith, and the inner end of the wrist pin 19 is solid as at 21 and has fixed therein the driving or crank pintle 22, eccentrically thereof, and 45 which pintle carries the crank arm 23 of the power unit which is pivoted as at 24 to the reduced end 25 of the pitman 8, thus forming a direct connection from the pumping piston 11 to the wrist pin 19. This latter, upon its inner end, is 50 provided with a circular covering plate 26 held in position against the pin by a suitable tap bolt 27, and, just inwardly of the union of the web of the pulley 20 with the wrist pin 19, the latter is 55 provided with a circumferential bead indicated at

28 for engagement with the inner surface or shoulder of the annular groove 29, about the interior of the outer terminus of the sleeve 18. The bead 28 functions as a thrust bearing for the 5 wrist pin, and just outwardly of this bearing is installed a suitable oil stop 30 to prevent any possible leakage of lubrication from the bearing. The outer open end of the wrist pin 19 may be closed as by the expansion plugs illustrated at 31.

10 In this embodiment I have illustrated the power for the unit as being supplied by an electric motor 32, but it is to be understood that this may be any other form of motor such as gasoline or the like without in any way departing from the spirit 15 of the invention. However the power therefrom is shown as being conveyed as by a belt 33 bearing directly upon the pulley 20, the same being known in the art as a V-belt, but in this instance only the smaller pulley of the motor is required 20 to be of V-shape.

The water end of the unit is of the usual four valve double acting type common in the art, and the valves of which are indicated at 34 operating alternately in pairs as the piston 11 is reciprocated, two being closed while the other two are open, and vice versa in respect to the discharge of water from the chambers 3-3 through the discharge opening 35, the intake opening of the pump being indicated at 36. The arrangement 25 of the valves 34 in this instance is such that all four of said valves are installed from above and into the upper wall of the chambers 3-3 or pump head of the unit, they being covered by the removable air chamber 37 which is held in place by 30 a suitable through bolt 38, as is common.

It is to be noted that the stuffing box 13 about the pump piston 12 is integral with the stuffing box 40 surrounding the pitman 8 and that they together form a covering member for the two 40 openings 41 and 42 into the pump end of the housing, and also that this covering member is held in position by any number of tap bolts such as indicated at 43, it being found only necessary to cover the stuffing box 40 about the pitman 8 45 with a cap 44 and suitable gasket 45 held thereby, this being sufficient for prevention of any oil being carried out of the housing by the pitman 8, while the stuffing box about the pump piston rod 12 is shown as provided with a common stuffing 50 gland and packing controlled by a novel form of pressure device 46, which is spring controlled to insure uniform pressure upon the gland.

Thus it is seen that by the removal of the coupling member 14, which rigidly carries the 55 end of the pumping piston rod 12 and is fixed to the end of the pitman 8, and the subsequent removal of the covering plate embodying the boxes 13 and 40, access is readily had to the pump cylinder and the interior of the inclined extensions 60 of the chamber 2 of the housing, such convenience obviously being for the installation of or repairs to the mechanism.

A further novel feature of this assembly is that the sleeve like member 7' forming the guide and 65 holder of the pitman 8 is divided into three bearing portions with open spaces intermediate of the end bearing portions and also a convenient space between the outermost one of said bearing portions and the end of the box 40 when the plate 70 carrying the latter is installed, so as to afford ample room for drippage of surplus oil being carried by the rod during its reciprocal action, and yet permitting same to utilize ample of the oil for necessary lubrication.

75 Furthermore it is to be noted that the cover

member 15 for the power end of the unit is provided with oil dripping fins 47 and 48 depending therefrom, and which fins convey oil splashed thereupon by the operation of the device onto both bearings of the crank arm 23, and that the 5 disc 26 has formed thereon opposite laterally projecting angular wings 49 for the purpose of carrying oil from the bottom of the chamber 2 about and splashing it promiscuously within said chamber to insure ample supply for the various 10 parts thereof.

The drippage of oil from the sleeve-like support 7' is conveyed by gravity upon the inclined bottom 50 back to the chamber 2, as clearly illustrated so that circulation of oil is constantly 15 taking place during the operation of the device, and is adequate for long time lubrication, which is so essential in such a unit.

Having thus described my invention, what I claim and desire to secure by Letters Patent, is:

1. A pumping power unit comprising a supporting housing upon and within one end of which the power supplying elements are supported and pumping mechanism upon and within the opposite end, characterized by means including a 25 pitman for transmitting energy from the power end of said housing to the pumping mechanism at the other end slidably supported beneath said pumping mechanism and connected thereto externally of said housing, and an oil chamber 30 common to said means and to all of the moving parts of the power elements within said housing.

2. In a pumping power unit, a supporting housing, a power supply shaft transverse one end of said housing, a pump and valves therefor in the opposite end of the housing and means including a horizontally slidably pitman operable beneath said pumping mechanism for transmitting energy thereto from said power shaft, and an oil chamber common to said means and to all of the moving parts of the power elements within said housing. 35

3. In a pumping power unit a supporting housing, a motor mounted upon one end of said housing, a combined water and air chamber mounted upon the opposite end of said housing, a power 45 transmitting shaft extending within said housing beneath said motor and driven thereby, a reciprocal sliding pitman extending through the opposite end of said housing for conveying power from said shaft to outwardly of said housing, and 50 a reciprocal pumping piston installed intermediate of said chamber and said pitman and rigidly connected to the latter externally of said housing.

4. A combined reciprocal piston pump and power unit including a supporting housing having 55 an oil containing chamber therein, a power shaft extending within said chamber adjacent one end thereof, a slidably pitman within said chamber operated by said power shaft and extending through the opposite end of said chamber, and 60 means for rigidly connecting said pump piston and pitman externally of said housing.

5. A pumping power unit comprising a supporting housing upon and within one end of which the power supplying elements are supported and pumping mechanism upon and within the opposite end, characterized by means including a single horizontally reciprocal pitman supported within said housing beneath said pumping mechanism for transmitting energy 70 from the power end of said housing to the pumping mechanism and connected thereto externally of said housing, there being an oil chamber common to said means and all of the moving parts of the power elements within said housing. 75

6. A combined pump and power unit comprising an elongated housing, power supplying elements at one end of said housing, pumping mechanism at the other end of said housing, said mechanism including a piston rod for operating same pumping mechanism, a slideable pitman beneath the pumping mechanism and connected with said piston rod for transmitting power from said

power supplying elements, a bearing for said pitman having spaced means to progressively diminish the carrying of oil toward the pump connection therewith, and an oil seal for said pitman to prevent the leakage of oil outwardly of said housing. 5
